VACUUM HEATING PUMP

Lloyd B. Gruman, Shippensburg, Pa., assignor to
Domestic Engine & Pump Company, Shippensburg, Pa., a corporation of Pennsylvania

Application September 26, 1938, Serial No. 231,845

12 Claims. (Cl. 103—6)

My invention relates broadly to vacuum pumps, and more particularly to a construction of vacuum pump adapted for use in a vacuum heating system.

5 One of the objects of my invention is to provide an improved construction of suction means for exhausting condensable and non-condensable gases from the heating system whereby circulation of steam through the heating system is assured, this suction means being disposed in juxtaposition with the system.

10 Another object of my invention is to provide an improved and simplified method and apparatus for exhausting fluids from a vacuum heating system and returning condensate to the boiler.

15 Still another object of my invention is to provide an arrangement of vacuum heating pump in which there is no lift pipe or check valve therein.

20 A further object of my invention is to provide an improved construction of receiver for the storage of condensate returns and using this condensate to supply heating water to the vacuum heating pump.

25 A still further object of my invention is to provide an arrangement of automatic float controlled mechanism in a receiver to effectively regulate the vacuum heating pump with respect to the changes in the vacuum heating system.

30 Another object of my invention is to provide an improved electric control system for the motor of a vacuum heating pump in a vacuum heating system.

35 Still another object of my invention is to provide improved means for adjusting pressure differences between the vacuum heating system and the vacuum pump so as to assure flow of condensate returns from the system to the receiver by gravity.

40 A further object of my invention is to provide a novel construction of ejector nozzle for establishing suction pressure in a vacuum heating system for effecting return of vapor and condensate to the receiver.

45 A still further object of my invention is to provide an improved construction of receiver for vapor and condensate in a vacuum heating system in which the vapor and condensate mixture is discharged into a confined baffled area within the receiver in a manner which prevents the vapor and condensate mixture from surging and excessively agitating the condensate already in the receiver and also separates the vapor from the condensate mixture.

55 Another object of my invention is to provide a construction of receiver for a vacuum heating pump which constitutes supporting means for the other parts of the pump and control mechanism and in which there is no accumulator base required.

60 A still further object of my invention is to

provide an improved construction of receiver for a vacuum heating pump which operates under atmospheric pressure while the pump is exhausting the vapor and condensate mixture from the system under vacuum and in which the vacuum is reflected back to the receiver after the pump is brought to rest.

5 Other objects and advantages of my invention will be apparent during the course of the following specification.

10 In the accompanying drawings, forming a part of this specification, and in which like numerals are employed to designate like parts throughout the several views:

float switch, the solenoid actuated valve and associated parts of the system of my invention.

My invention is directed to a vacuum heating pump unit which includes a motor driven pump which pumps a stream of water from a receiver and forces this stream through a single or multi-ported ejecting nozzle which creates a high suction pressure head for pumping vapor and condensate from the vacuum heating system. The vapor and condensate, together with a portion of the circulating water stream, is delivered to the receiver. The gases are vented from the receiver and as water accumulates in the receiver beyond a predetermined level, the excess water is forced by the pump to the boiler of the vacuum heating system.

The construction of my invention does not include a lift pipe or a check valve therein at any point in the suction line of the vacuum pump. The vacuum which is established is effective to draw steam through the vacuum heating system without interposing a check valve in the path of the circulating medium. The system of my invention will operate under any conditions where-
as prior systems require a check valve in the suction line of the vacuum pump.

One of the principal features of my invention is the fact that the vacuum created in the heating system is reflected back into the receiver in its entirety at the closing down of the unit. The unit during its idleness is always under the heating system conditions, that is, from the predetermined vacuum settings which are usually from three to eight inches of mercury.

The condensate from the vacuum heating system is allowed at all times and under any prevailing vacuum to return to the receiver by gravity providing the returns are above the unit. A vacuum switch is provided which maintains a predetermined degree of vacuum throughout the heating system at all times. A float switch controlled by the level of the condensate in the receiver is provided, the float switch being independent of the vacuum switch in operation, and operating an electrically controlled discharge valve in the discharge line of the pump whereby, the accumulated water in the receiver is returned to the boiler.

It is impossible to lose the hurling water under sub-normal conditions that may prevail in the system, such as sub-atmospheric conditions which are caused by the banking of fire in a boiler, which in turn creates a high vacuum in the boiler which reflects back to the pump discharge line through the discharge line and would siphon the entire hurling water from the unit were it not for the fact that I have balanced the vacuum in the receiver and the system return line and further by the fact that the electrically controlled discharge valve remains closed functioning only when high water level is reached in the receiver. In other words the hurling water is not lost under any conditions except by natural vaporization. The arrangement of my invention may operate under either atmospheric or vacuum conditions and the hurling water is not lost. The vacuum heating system is operative with pressure, either above or below atmospheric pressure on the boiler as well as varying degrees of vacuum on the system.

The location of the nozzle in a horizontal position above the water level in the receiver also provides a novel arrangement in the construction of my invention. When the system returns
75 are above the inlet of the vacuum pump the

latter is not called upon to do any work for the purpose of lifting the condensate returns within the receiver and therefore does not sacrifice any degree of vacuum for purposes of lifting the fluid as is the case in prior systems.

The pump is capable of discharging a portion of the water from the receiver to the boiler simultaneously with the discharging of the water from the nozzle to the ejector for creating a vacuum and assuring recirculation in the vacuum heating system.

Referring to the drawings in detail, reference character 1 designates the receiver of the vacuum heating pump. The receiver actually provides the supporting means for other parts of the pump and there is no accumulator base required. Suitable securing bolts 2 allow the receiver to be anchored to a cement base or other form of support. The receiver 1 contains a baffle member 3 which prevents excessive surging or agitation within the receiver upon the condensate within the receiver and separates the vapor from the mixture returning from the heating system.

The baffle 3 of receiver 1 divides the receiver into two compartments 12 and 12a. The baffle 3 is provided with an opening 3a which extends slightly below the normal water level in the receiving tank as shown in Fig. 2. This provides a means of communication between the two compartments 12 and 12a.

The compartment 12 is provided near its bottom with a clean-out opening 74, which is enclosed by a cover 75, the cover being secured in place by top bolts 76.

The numeral 9 designates an ejector body which is substantially tubular in shape, having an outwardly extending flange 9a for rigidly securing the same to the side of the receiving tank 1. The tube 9 is carried inside the tank 1 and extends transversely adjacent the top thereof through the baffle 3 and is curved at 10 to deliver the vapor and condensate mixture through the orifice 11 directed into open compartment 12. The mixture of condensate and vapor is directed under pressure against the interior side wall 14 of the compartment 12. The reaction or splashing of the vapor and water upon the mixture in the compartment 12a is prevented by the projecting baffle 3, which prevents excessive agitation of the condensate already in the compartment 12a.

The numeral 5 designates a casing adapted to house the suction chamber 71, and the passages 4 and 32 leading thereto. The casing 5 extends horizontally from the side wall of the receiving tank 1 and is disposed thereon so that opening 7a registers with the opening in the tubular ejector body 9. Ejector nozzle 6 is mounted interiorly of the casing 5 in horizontal alignment with ejector tail piece 7. Nozzle 6 has its end 78 open to receive the hurling water from the pump and its other end foraminated as at 6a for discharging the hurling water under pressure through the ejector tail piece 7 which is axially aligned but spaced apart from the nozzle 6. The ejector tail piece 7 is carried by the ejector body 9 and projects into the casing 5 through the opening 7a. The ejector tail piece 7 is substantially in the shape of a Venturi tube as indicated at 8 for receiving the discharge from the nozzle 6. The intermediate portion 8a of Venturi tube 8 is of 70 smaller diameter than the opposite ends. The end 79 of Venturi tube 8 is flared outwardly to decrease the velocity of the stream before it is discharged into the ejector body 9. The action of the ejector is to produce a suction in the pipe 75

4 which serves as a return from the vacuum heating system and communicates with the casing 5 at the opening 4a at substantially right angles to the axes of the nozzle 6 and ejector 7. The suction thus produced draws into the ejector body 9 of the vapor condensate, air and mixtures thereof from the vacuum heating system.

The condensate is collected in receiver 1 and operates upon the float ball 15 which is connected through arm 16, journaled at 17 to supporting member 87 and connected through a bellows 18 to the actuating member 19 of a suitable float switch contained within housing 20.

The numeral 80 designates a flange which is preferably integrally cast with the side wall of the compartment 12a of receiver 1. The flange 80 is cored out at 81 forming the opening through which bellows 18 extends. Flange 80 contains a plurality of screw threaded openings 82 for receiving the screws 84 which hold plate 83 in position over the opening 81. The plate 83 has a centrally located slot 85 through which the end 86 of the bellows 18 projects and which forms a watertight joint therewith. Flange 80 provides means for mounting supporting member 87 heretofore described, through the opening 81. Member 87 projects into receiver 1 substantially normal to the side wall thereof. Parallel strips 88 and 89 are carried near the end of the supporting member 87 and serve to hold the adjusting screws 90 and 91 which limit the movement of the ball 15 by abutment with the end 16a of the arm 16.

When the float switch is closed by the rise of the condensate in receiver 1, a circuit is completed to the driving motor 21 and electrically controlled valve 22 in association with the starter indicated at 23 as shown more clearly in Fig. 24.

The motor 21 drives impeller 24 in pump 25 having suction intake connection 26 and pump discharge connection 27 which register with the suction and discharge ports 28 and 29 respectively in one side of receiver 1. The pump 25 is securing fastened to the receiver 1 by means of the tap bolts 95. The rotary impeller is keyed as indicated at 90 on the inwardly projecting end portion of the motor shaft 91. This impeller is formed internally with a circular series of substantially radially extending passages 92 separated by webs 93. It will be noted that these webs curve rearwardly somewhat away from the direction of rotation of the impeller. Surrounding the rotary impeller is an annular passage which communicates with the discharge passage 27. The suction port 28 leads directly into the receiver 1, and the hurling water, flowing through the passage 26 passes around hub 94 of the rotary impeller 24 which guides the stream to divert and disperse the hurling water into the several passages 92. Centrifugal force imparted by the driven rotary impeller 24 imparts high velocity to the hurling water from the periphery of the impeller 24 and directs the hurling water into the discharge channel 27 and through the discharge port 29 in the side of the receiver 1. The discharge port 29 communicates with a tubular conduit 30 cored directly into the wall of receiver 1, which extends inwardly from said wall and leading upwardly at an angle adjacent thereto. Conduit 30 discharges at 31 both into the passage 32 in the casing 5 leading to the ejector nozzle 6, and into the discharge line 33, controlled by valve means 34 of the electrically controlled valve 22, to the discharge line 35 leading to the boiler.

The water which is forced through passage 32 is discharged under pressure through the apertures in the foraminated end 6a in the head of the nozzle 6 into ejector tail piece 7, establishing the vacuum hereinbefore described. A clean-out plug 36 is provided in casting 5 in alignment with nozzle 6 and ejector tail piece 7.

Communicating with the passage 32 at the point 96 is an auxiliary pipe 37 for receiving a portion of the hurling water under pressure. The hurling water is delivered to the air relief valve 38 shown more clearly in Fig. 23 comprising a casting 97 which is substantially circular in cross section, having air relief chamber 101 therein and screw threaded opening 104 to receive the member 98. Member 98 is provided with a screw threaded opening 99 in its rearward end for receiving the auxiliary pipe 37, the forward end having an annular groove 100 at its periphery forming a seat for the bellows 39. The forward end of the casting 97 is closed except for the passage 102 which forms a valve seat 41 at its junction with the air relief chamber 101. The forward end of the passage 101 is adapted to receive the pipe 42 which connects at its other end with the receiver 1 at the point 43. The bellows 39 contained within the air relief chamber 101 has its rearward end seated in the annular groove 100 of the member 98. Arranged at the forward end of the bellows 39 is valve 40 which remains seated on valve seat 41 as long as hurling water is being forced through passage 32 by pump 25, thereby preventing breaking down of vacuum in the system. However, upon cessation of operation of the pump 25 the pressure in passage 32 is reduced and the bellows 39 collapses, opening valve 40 with respect to valve seat 41, permitting air from the receiver 1 to return to the inlet 4 via the short pipe 46 which connects with the under side of the casting 97 at 103 and has its other end communicating with the inlet pipe 4 thus assuring equal pressure throughout the system.

Arranged above the casting 97 is a vacuum and pressure gauge 44 connected thereto at 45. The gauge 44 is operatively connected to the intake pipe 4 through chamber 101 and connecting pipe 46.

In order to predetermine the limits of operation of the vacuum heating system, a vacuum switch is provided as indicated at 47 in Fig. 1 which may be set to operate over a range, for example, of from 3 to 8 inches of mercury. The vacuum switch 47 is controlled by a diaphragm actuator indicated at 48. One side of the diaphragm 48 is exposed to the suction inlet in the return from the system at 4 through the connection 49. Diaphragm 48 is therefore displaced in proportion to the vacuum in the system, and in order to prevent an excessive vacuum in the system a safety valve or vacuum breaker is provided as indicated at 50 connected with the intake passage of suction pipe 4.

Using the arbitrary figures of three to eight inches of mercury as an example, it may be assumed that the vacuum within the system falls below the minimum point. As indicated in Fig. 24 the valve pusher 48 of vacuum switch 47 closes the contacts 105 and 106, and energizes the relay R₃ which actuates the starter switch 107, thus closing contacts a—h, b—g, c—f, and d—e. Switch 107 is preferably mounted within a housing 23 supported above the motor 21 as shown in Figs. 1 and 3. Overload relays R₁ and R₂ control contacts 108 and 109 in circuit with 75

the relay R_3 . Even though the float switch 20 is still open, the vacuum switch 47 will start and maintain the motor 21 in operation until sufficient vacuum is attained.

One pair of contacts in the float switch is wired in parallel with the vacuum switch circuit, for separately controlling the relay R_3 through contacts 108 and 109 for energizing the motor 21 through switch 107 . The electrically controlled valve operating winding 22 is wired in series with contacts b, g , of the starter switch 107 , and with another pair of contacts in the float switch and therefore is not affected by the vacuum switch 47 . If the level of the condensate in receiver 1 should get too high the float switch 20 would cut into the circuit, energizing the electrically controlled valve operating winding 22 which in turn operates the valve 34 increasing the flow of water to the boiler and lowering the condensate in the receiver 1 until the float switch 20 is lowered to a position permitting it to break the contact and thus deenergize the electrically controlled valve operating winding 22 , closing the valve 34 . The valve 34 is never opened while motor 21 and pump 25 remain at rest, as the float switch 20 will operate to energize the motor at the same time valve 22 is energized, if the motor is not already energized under control of vacuum switch 47 .

The receiver 1 is provided with a gauge glass 51 interconnected at 52 and 53 with different levels in the receiver 1 for indicating the condensate level within the receiver 1 . A thermometer may be mounted in any convenient position in the receiver 1 below the normal condensate level or within the passage 32 in a convenient location through plug 36 in alignment with nozzle 6 .

In order to insure against flooding of the receiver 1 a safety float valve indicated at 54 is provided, located in a position adjacent the top of the receiver 1 , as shown more particularly in Figs. 12-20.

The receiver 1 contains an opening 110 in its top which is covered by the valve body 58 , the valve body being securely fastened thereto by means of suitable screws 111 .

The valve body 58 includes a vapor discharge chamber 112 arranged above the top of the receiver 1 , leading to the atmosphere through the opening $112a$. Valve body 58 also includes hollow bifurcated depending portion 57 which extends downwardly through the opening 110 into the receiver 1 . Each of the depending portions 55 communicates with the receiver 1 by means of openings 66 contained in their inner sides 113 . The openings 66 both connect with the vapor discharge chamber 112 through the passage 114 , which is provided through a tubular valve seat 67 . Axially aligned with the valve seat 67 is a hollow plug 115 , screw threaded into the opening 116 in the valve body 58 . The cap of plug 115 is internally cored as at 117 forming a spring seat for the light spring 70 which rests in the socket 117 and encircles the stem 71 of disc valve 68 located on the tubular valve seat 67 .

The float 54 is connected through rocker arm 55 to rocker 61 which is journaled at 56 between the bifurcated depending portion 57 of the valve body 58 . The rocker 61 is angularly movable between the depending portion 57 and is provided with limiting stops 59 and 60 .

Member 61 carries discs 64 which are spring pressed by means of spring 65 as shown in Figs. 15, 16 and 20, to bear outwardly against the

valve seats provided at each of the passages 66 in the bifurcated portion of the valve body 58 . In Figs. 13 and 16 the passages 66 are illustrated as closed by the discs 64 which is the condition when the receiver 1 becomes flooded, and wherein limiting stop 59 bears against depending portion 57 of the valve body 58 . When, however, the receiver is functioning in a normal manner, float 54 is dropped into lowermost position and limiting stops 59 contact with the side of depending portion 57 of valve body 58 . In this position, discs 64 uncover the ports 66 and there is a direct passage from the interior of receiver 1 through the depending portion 57 of valve body 58 , through the tubular valve seat 67 and beneath the disc valve 68 to the atmosphere through opening $112a$. It is very important that extremely light pressure be applied against disc valve 68 . Excessive pressure on disc valve 68 will immediately reflect upon the efficiency of the pump as the non-condensable gases and vapors are vented therethrough.

In operation of the apparatus of my invention, the rotating impeller element 24 of pump 25 is set in motion by an automatically controlled motor 21 actuated by an automatic starter 23 through either the vacuum regulator 47 or the float switch shown at 20 . Hurling water which does not recede below a predetermined minimum level in chamber or compartment $12a$, flows into intake connection 26 of the pump, entering the inlet to the impeller 24 , and is discharged by the impeller into channel 30 cast integral with the receiver and through the communicating passage to nozzle 6 . The high velocity water jet passing through the ejector gap creates a vacuum in passage 4 leading to the system from which vapors and condensate are drawn. The mixture is compressed in the ejector throat and discharged through ejector tube 8 into air separating chamber $12a$, and the vapor and air are vented to atmosphere through the float operated air valve shown in Fig. 12 while condensate accumulates in storage chamber 12 and $12a$.

During the process of creating a vacuum on the system, and also when the pump is at rest and returns are above the pump inlet, condensate accumulates in chamber 12 and $12a$, ultimately reaching a level at which float 15 actuates float switch 20 , thus completing the electrical circuit and simultaneously opening the electric discharge control valve 34 permitting the accumulated condensate to be discharged through a suitable check valve (not shown) into the boiler. When the unit is on vacuum or continuous service both control valve 34 and the float switch 20 are operable with starter 23 .

Summarizing, with vacuum switch 47 closed and motor 21 driving the pump 25 , a vacuum is established in the suction chamber 77 which draws the gases and condensate from the vacuum heating system through the return or inlet duct 4 . The hurling water, circulated by pump 25 , carries the gases and condensate from the heating system into the receiver 1 so that the level of water in receiver 1 gradually rises and bears float 15 upward. At a predetermined water level, float switch 20 is actuated and operates to open valve 34 which passes a portion of the water from pump 25 to the boiler, thus lowering the level of water in the receiver until float switch 20 is opened.

Under these operating conditions, where motor 21 is running, relief valve 40 is seated so that the pressures in the suction chamber 77 and the

receiver 1 are different. When an adequate vacuum has been established, however, and motor 21 is disconnected by operation of vacuum switch 47, valve 40 opens and the pressures in the chamber 77 and the receiver 1 are equalized through pipe 42 at substantially the degree of vacuum prevailing in the system, to prevent a differential of pressure which otherwise might act to drive the water in the receiver back into the chamber 77 and duct 4.

The air relief valve shown at 40 may be of all brass construction, and its primary function is to serve as a means of bypassing trapped air in the receiver 12-12a to the return inlet 4, when the pump 25 is idle, thus assuring free flow of condensate from the system through the ejector throat into the receiver. During the operation of the pump 25 the valve remains closed as the discharge pressure acts upon the bellows 39, and the vapor and air extricated from the system are thus discharged through combined vacuum and air relief valve 68.

Non-condensable gases are vented to the atmosphere through valve 68 so long as the level of water in the receiver is maintained within the limits determined by operation of float switch 20. Under conditions of an excess of condensate accumulating in the receiver 1, even with valve 34 open, the level of water in the receiver tends to rise above the desired level. In such instances, float 54 is borne upward and operates to close the ports 66 and thereby trap the non-condensable gases in the receiver. A back pressure, therefore, is built up in the receiver which reduces the effective operation of pump 25 to maintain the same degree of vacuum, and at the same time increases the output of water to the boiler through valve 34 by reason of the increased pressure in the receiver. The excess water is thus delivered to the boiler and the water level in the receiver again falls to within the limits of control by float switch 20, valve 34 remaining open until the circuits through switch 20 are opened.

The primary purpose of the valve shown in Fig. 12, therefore, is to eliminate spilling of condensate through the air discharge port 112a, and also to prevent air leakage when the receiver goes under vacuum. The valve body 58 may be of cast brass, and the air discharge valve 68, valve seat 67, and float arm 61 of bronze. The float 54 may be of copper, while float valve discs 64 and spring 65 may be of stainless steel. The spilling aforementioned is the result of any of the following conditions:

1. Pump 25 may not be operating.
2. Discharge pressure may be greater than pressure for which the pump is designed, which may be due to:
  - (a) Discharge line too small (increased friction head).
  - (b) Discharge line too long (increased friction head).
  - (c) Static head greater than originally figured.
  - (d) Boiler pressure greater than originally figured.

Under any of the above conditions, the pump 25 cannot deliver condensate to the boiler until the condensate rises in the receiver 12-12a, raising float 54 and closing the air vent passage through 66. When this occurs, receiver 12-12a is subjected to pump pressure when pump 25 is running, and this acts upon the inlet side 26 of im-

peller 24, and as long as the valve ports 66 remain closed, the pump 25 discharges against the greater pressure.

In the event the load on motor 21 ever becomes too great for safety, from various causes, the overload release relays R₁ and R₂ operate to disconnect the motor by deenergizing relay R₃, whereupon valve 40 opens and pressures in chamber 77 and receiver 1 are equalized preparatory to resumption of the cycle of operation. Valve 34 is closed simultaneously with disconnection of the motor. Motor 21 is again energized by restoration of the relay circuits, and the apparatus resumes normal operation with the float control members 15 and 54 effective with their respective normal ranges of operation.

The apparatus of my invention has been found highly practical in its construction and operation. It will be observed that all of the equipment is mounted upon the receiver as a support 20 and that there is no accumulator base required. This arrangement provides a highly compact assembly and greatly simplifies installation. The number of parts of the vacuum heating pump have been maintained at a minimum so that replacement of parts and maintenance expense is greatly reduced.

In the specification and claims where I have referred to "hurling water," I refer to the quantity of water of predetermined depth in the receiver 1 limited by the operation of ball float 15. By "condensate returns" I mean the accumulated water in the heating system delivered to receiver 1 by gravity or vacuum. The term "air and vapor" as used herein, refers to the gases, 35 steam and other vapor held within the boiler and system and pulled into the receiver by the ejector nozzle where the condensable components are liquefied and added to the condensate returns.

I desire that it be understood that the form 40 and application of my invention herein shown and described is to be taken as a preferred example of the same, and that various changes in the shape, size and arrangement of parts may be resorted to, without departing from the spirit 45 of my invention or the scope of the appended claims.

What I claim as new and desire to secure by Letters Patent of the United States is as follows:

1. In a vacuum heating pump unit, the combination of a pump, driving means for said pump, a receiver having space for hurling water and storage space for condensate, inlet and outlet means for said receiver, an ejector nozzle system operative for creating a vacuum in said inlet means, a connection between said pump and said nozzle system for forcing a suitable liquid through said ejector nozzle system, said outlet means comprising a branch from said connection, an open conduit for carrying liquid from the receiver to 60 the suction inlet of the pump, means for carrying the liquid and vapor and condensate mixture drawn by the vacuum through said inlet means from the ejector nozzle system to the receiver, and a valved pipe means connecting said receiver 65 and said inlet means for automatically equalizing the pressures therein when said pump is idle.

2. In a vacuum heating pump unit, the combination of a pump, drive means for said pump, a receiver having a fluid outlet connection from 70 said receiver to the inlet of said pump, space for hurling water and storage, a vertically disposed baffle member having an opening near its top which serves to divide the receiver into a right and a left chamber, a fluid entrance conduit en- 75

- tering the left chamber of said receiver, extending adjacent the top thereof and through the opening in the baffle member and discharging into said right chamber of said receiver, said conduit having an inlet for vapor and condensate return mixture, said pump having an outlet arranged to direct condensate from said receiver through said fluid entrance conduit for drawing said return mixture into said receiver, a discharge conduit for fluid connected with the outlet of said pump, and a liquid level control means arranged interiorly of said receiver and electrical connections controlled thereby for controlling said drive means and the passage of fluid in said discharge conduit for maintaining said liquid level substantially constant.
3. In a vacuum heating pump unit, the combination of a pump, drive means for the pump, a receiver connected with said pump and having space for hurling water and storage space for condensate, said receiver having inlet and outlet means, means including said pump operative to effect a vacuum in said inlet means, and a combined vacuum and air relief valve in said receiver, comprising a casing member externally of said receiver having exit means to the atmosphere and a depending portion which extends into the receiver, said depending portion being hollow and having ports opening into the receiver and communicating at their other end with the casing member external to the receiver, a valve means for controlling communication therebetween, a float, a rod pivotally connected to the depending portion and carrying the float on its other end, and means operable by said float for closing the ports contained by said depending portion.
4. In a vacuum heating pump unit, a pump, drive means for said pump, a receiver having inlet and outlet means, said pump being connected with said receiver, a fluid injecting nozzle connected with said pump and having a foraminated outlet, a Venturi tube aligned with the foraminated outlet of said nozzle and spaced therefrom, an ejector tube connected with said Venturi tube for directing fluid media into said receiver, and means for rendering effective the vacuum established between the foraminated head of said nozzle and said Venturi tube for delivering vapor and condensate from said input means through said ejector tube to said receiver, a partition member in said receiver dividing the receiver into a pair of compartments, said ejector tube being supported by said receiver and projected into the receiver adjacent the top thereof, and extending over one of the compartments in said receiver and terminating in the other of the compartments in said receiver for delivering vapor and condensate to one of the compartments in said receiver.
5. In a vacuum heating pump unit, in combination with a receiver, a housing disposed adjacent one side of said receiver and providing an inlet chamber for condensate and vapor, a nozzle supported in one wall of said housing, a Venturi tube supported in the opposite wall of said housing in alignment with said nozzle and projecting into said receiver, means including said Venturi tube for securing said housing in fixed relation to said receiver, said nozzle and said Venturi tube terminating in spaced relation within said inlet chamber, and means for establishing a fluid pressure discharge from said nozzle through said Venturi tube across the space therebetween within said inlet chamber for entraining vapor and condensate delivered to the inlet chamber for discharge into said receiver.
6. In a vacuum heating pump unit, the combination of a pump, drive means for said pump, a receiver connected with said pump and having space for hurling water and storage space for condensate, inlet and outlet connections for said receiver, means including said pump operative to effect a vacuum in said input means, a bifurcated depending support carried by the upper portion of said receiver, valve seats formed on opposite sides of the bifurcated support and connected with passages extending through said bifurcated support to a valved vent leading to the atmosphere, a pivotally mounted lever member, a valve carried by said lever member and coacting with the valve seats on said bifurcated support, and a float connected with said lever member for opening or closing said valve with respect to the valve seats according to the level of fluid in said receiver.
7. In a vacuum heating pump unit, the combination of a pump, drive means for said pump, a receiver having space for hurling water and storage space for condensate, a vacuum heating system return pipe connected with said receiver, a vacuum producing device supported with respect to said receiver and including a collecting chamber for receiving vapor and condensate from the vacuum heating system return pipe, a nozzle extending into one side of said collecting chamber, a Venturi tube extending into the other side of said collecting chamber in spaced relation to and in alignment with said nozzle, the opposite end of said Venturi tube extending into said receiver, a tubular nozzle connected with said Venturi tube and extending transversely of said receiver for discharging vapor and condensate adjacent one wall thereof, and a boiler feed pipe having a connection with said pump, said pump being supported by said receiver and operative to force fluid from said receiver into two branched paths, one of said paths leading to said first mentioned nozzle and the other path leading to said boiler feed line.
8. In a vacuum heating pump unit, the combination of a pump, drive means for said pump, a receiver having space for hurling water and storage space for condensate, said receiver being connected with said pump, outlet means for said receiver connected with said pump, a vacuum producing device mounted adjacent said receiver, said vacuum producing device including a chamber for receiving vapor and condensate, a fluid discharge nozzle mounted in one wall of said chamber and connected with said pump, a Venturi tube mounted in the opposite wall of said chamber and extending into the upper portion of said receiver, said Venturi tube being disposed in alignment with said discharge nozzle and terminating in spaced relation with respect thereto for providing a gap within said chamber for entraining vapor and condensate from said chamber and delivering the same to said receiver when fluid from said pump is discharged under pressure through said nozzle, and a by-pass connection between the said chamber and the said receiver controlled by the pressure in said nozzle for establishing a connection directly between said chamber and said receiver when no pressure exists in said discharge nozzle.
9. In a vacuum heating pump unit, a receiver, an air vent valve in said receiver comprising a casing member carried externally of said receiver having discharge means to the atmosphere and a

- depending portion which extends into the receiver, said depending portion being hollow and having ports opening into the receiver and communicating at their other end with the casing member external to the receiver, a valve means 5 for controlling communication therebetween, a float, a rod pivotally connected to the depending portion and carrying the float on its other end, and means operable by said float for closing the ports contained by said depending portion.
- 10 10. In a vacuum heating pump unit, a receiver, inlet and discharge connections for said receiver, a bifurcated depending support carried by the upper portion of said receiver, valve seats formed 15 on opposite sides of the bifurcated support and connected with passages extending through said bifurcated support to a vent leading to the atmosphere, a pivotally mounted lever member, a valve carried by said lever member and coacting with the valve seats on said bifurcated support, and a 20 float connected with said lever member for opening or closing said valve with respect to the valve seats according to the level of fluid in said receiver.
- 11 11. In a vacuum heating pump unit, a boiler 25 feed pipe, a receiver, a vacuum heating system return pipe connected with said receiver, said receiver having a connection to said boiler feed pipe, a suction generator supported with respect to said receiver and including a collecting chamber 30 for receiving vapor and condensate from the vacuum heating system return pipe, a nozzle extending into one side of said collecting chamber, a Venturi tube extending into the other side of said collecting chamber in spaced relation to 35 and in alignment with said nozzle, the opposite end of said Venturi tube extending into said receiver, a tubular nozzle connected with said Venturi tube and extending transversely of said
- receiver for discharging vapor and condensate adjacent one wall thereof, and a pump supported by said receiver and operative to force fluid from said receiver into two branched paths, one of said paths leading to said first mentioned nozzle and 5 the other of said paths leading to the boiler feed pipe.
12. A vacuum heating pump unit including a receiver chamber, suction intake and pressure output ports connected with said receiver chamber, pump means for producing suction at said intake port and pressure at said output port, pressure equalizing valve means between said suction intake port and said receiver chamber controlled by the pressure in the aforesaid means, 10 valve means in said output port controlled by the level of water in said receiver chamber, vent means for said receiver chamber provided with a check valve, and cut-off valve means for said vent means controlled by the level of water in said 15 receiver chamber; said pump means being operative to close said equalizing valve means and produce a suction pressure in said intake port for delivering vapor and condensate mixture to said receiver chamber, said output valve means being 20 opened for delivering excess water through said output port as the level of water in said receiver chamber rises with the addition of said condensate thereto, said vapor being passed through said vent means, and said cut-off valve means being 25 operated upon continued rise of the level of water in said receiver chamber for closing said vent means and producing a pressure condition in said receiver effective to increase the net discharge of water through said output port for restoring the normal level of water in said receiver. 30 35

LLOYD B. GRUMAN.
